(57) **CLAIM**

The ornamental design for an interactive transparent surface table, as shown and described.

DESCRIPTION

FIG. 1 is a front perspective view of an interactive transparent surface showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a front perspective view of the interactive transparent surface table showing a transparent display part in an opened position;

FIG. 8 is a front view of the interactive transparent surface table showing the transparent display part in an opened position;

FIG. 9 is a rear view of the interactive transparent surface table showing the transparent display part in an opened position;

FIG. 10 is a right side view of the interactive transparent surface table showing the transparent display part in an opened position;

FIG. 11 is a left side view of the interactive transparent surface table showing the transparent display part in an opened position; and,

FIG. 12 is a top view of the interactive transparent surface table showing the transparent display part in an opened position.

The shade lines in the Figures show contour or transparency and not surface ornamentation.

The broken lines in the FIGS. 1-4, 7-10 show portions of the interactive transparent surface table which form no part of the claimed design.
